UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

1,324,086.

Specification of Letters Patent.

Patented Dec. 9, 1919.

Application filed April 12, 1919. Serial No. 289,627.

To all whom it may concern:

Be it known that I, FRANKLIN R. WHITE, a citizen of the United States, and a resident of Waterbury, in the county of New Haven 5 and State of Connecticut, have made and invented certain new and useful Improvements in Buttons, of which the following is a specification.

My invention relates to a new and useful 10 improvement in buttons, and particularly to the type or kind that is employed with a staple provided with two or more prongs which are adapted to pierce their way through an imperforate base of the button, then through 15 an anchor located in the hub of the button, and then returned or bent or upset against an anvil located in the upper portion of the body of the button; and over which anvil is located the top or face plate of the button.

20 The invention also relates to that form or type of button as shown in the patent to Thomas W. Porter, No. 1,179,034, and issued April 11, 1916.

The present invention, however, contemplates improvements over the above-mentioned button, in that the present anchor is used not only to provide additional points of contact with the staples and to hold the button more rigidly to the cloth, but also 25 30 tends to direct the prongs of the staple in a vertical position after they have pierced the base of the hub of the button.

In other forms of buttons of the same general type it sometimes happened that 35 after the staples had pierced the imperforate hub they would be deflected and instead of remaining in an upright position and jam against the anvil they would pierce the sides of the upper plate of the anchor rather 40 than at a point near the center as designed.

With this and other objects in view, my invention consists in certain new and novel arrangements and combinations of parts as will be hereinafter more fully described and 45 pointed out in the claims.

Referring to the drawings, Figure 1 is a 50 sectional view of the button and cloth, and a staple in elevation, before it is forced into the cloth and button;

Fig. 2 is a similar view but with a staple forced into its final position;

Fig. 3 is a top plan view of the assembled button, a portion of the top plate and anvil being broken away for the sake of clearness;

Fig. 4 is a view similar to Fig. 2 showing,

however, the end of the staples deflected in a different position;

Fig. 5 is a perspective, looking from the bottom of the anchor;

Fig. 6 is a perspective of the anvil; and 60

Fig. 7 is a perspective of a modified form of anchor.

Referring now to the drawings, it will be seen that my improved button consists of a body portion 1 which is bent downwardly 65 as at 2 to form the hub of the button in the form of a hollow shell and located centrally of the bottom or base plate of the hub is the slight circular depression 3, and an upwardly pressed annular groove or 70 ring 4. The upper part of the body portion is flared slightly as at 5, and resting directly over the hub 2 and in the body portion is the anvil 6.

Before the anvil, however, is placed within 75 the button, an anchor 7 is placed therein, which anchor has the upright sides 8 and the imperforate base plate 9. The base plate 9 is a duplicate or replica of the base plate of the hub, it also being provided with a 80 slight central depression 10 and an annular depressed (as viewed from the bottom) ring 11.

This anchor 7 is preferably stamped from 85 a thin ribbon of cold rolled steel and adjacent its upper edges are formed the slightly upward and outwardly extending arms 12. These arms being of steel, possess, therefore, a certain amount of springiness or resiliency, and when the anchor is first placed 90 in the hub of the button they do not contact throughout their length with the inner surface of the body portion but extend slightly upwardly. A top plate 13 is then forced over the flared upper edge 5 of the body portion, which forces the anvil 6 against the anchor, thereby compressing the resili- 95 ent spring arms 12.

This is a very desirable feature as it 100 performs two functions, first, the spring arms, being under constant compression, hold the anvil against the top plate, thereby preventing any rattling of the same; and, second, the arms retain or hold the anchor from being pulled down when the staple 105 is forced through the same when the button is being attached to the cloth.

To secure the button to the cloth, a staple 110 14 is shown which is provided with the two metal prongs 15. After the button has been

placed in its desired position, the prongs 15 of the staple 14 are forced through the cloth 16, perforating the base plate of the hub, the ends of the prongs being guided 5 by the sides of the annular groove 4. After these prongs have perforated this metal, they will continue upwardly and if for any reason they should have become slightly deflected they will abut against the side walls 10 of the annular groove 11 formed in the base 9 of the anchor 7, which will again return them to their vertical or upright positions. The prongs continuing upwardly will impinge against the anvil 6 and the ends of the 15 prongs will be deflected over into the annular ring 11, the prongs becoming slightly flattened against the anvil, as shown in Figs. 2 and 4.

These prongs may either assume the position as shown in Fig. 2 or in Fig. 4, or in fact may be turned at any angle, depending probably on the metal at the end of the prongs. In other words, it cannot be determined at just what angle the prongs will 20 be deflected, but in all events they will be flattened and project downwardly into the groove of the anchor, thereby securely fastening the body of the button to the cloth.

In Fig. 7 I have shown a slightly modified 30 form of anchor 7', having the upright sides 8', a base plate 9', a depression 10', and an annular ring 11'. This anchor, however, is not provided with the spring arms 12, and is simply wedged or jammed down into the 35 hub of the button and of course held in position by the staple after it has pierced the same.

The advantages of an anchor in a button are well known, it providing a double contact 40 with the staple, thereby preventing the button from wobbling, and with the anchor of the present form the further advantages are secured of correctly directing the prongs of the staple in their upright position.

I am aware that it is old to use an anchor 45 in a button and do not claim the same broadly, but what I do claim is:

1. A button comprising a top plate, a body, and a hollow hub with an imperforate base 50 at the lower extremity thereof, said base provided with an annular groove spaced a distance from the outer periphery thereof, an anchor located within said body, the base plate thereof being a replica of the base plate of the hub; an anvil located in the upper part of said button, and the top plate 55 wedgedly holding the several parts in their fixed positions.

2. A button comprising a body portion 60 with a hollow hub and an imperforate base plate provided with an annular groove and a downwardly extending central portion, an anchor located in said body, and said anchor likewise provided with an annular groove 65 and a downwardly extending central por-

tion; an anvil located in the body portion of said button.

3. A button comprising a body portion and a downwardly extending hollow hub, 70 said hub provided with an imperforate base plate having an annular groove located therein, and a central depression; an anchor wedgedly held in said hub and provided with an annular groove in the base thereof; an anvil located in said body portion, and a top plate secured to said body portion and holding said anchor in said body portion.

4. A button comprising a body portion including a hub with an imperforate base 80 plate, the base plate having an annular groove, an anchor located in said body portion and provided with an imperforate base plate having an annular groove in substantial alinement with the annular groove of 85 the hub, and an anvil located in the body portion of the button above said anchor and fixedly held in place.

5. A button comprising a body portion including a hub with an imperforate base 90 plate, the base plate having an annular groove, an anchor located in said body portion and provided with an imperforate base plate having an annular groove in substantial alinement with the annular groove of 95 the hub, and an anvil located in the body portion of the button above said anchor and fixedly held in place, said anchor being provided at its upper extremity with spaced resilient arms.

6. A button comprising a body portion having a hub in the form of a hollow shell and a base plate provided with an annular groove and a central depression; an anvil in 105 said body portion, a top plate secured to said body portion; a staple; and means located in the shell of the body portion for correctly alining the prongs after piercing the base plate of said button and before they impinge against said anvil, said means including a 110 base plate having an annular groove and a central depression.

7. A button comprising a top plate, a body, and a hollow hub with an imperforate base 115 at the lower extremity thereof, said base provided with an annular groove spaced a distance from the outer periphery thereof, an anchor located within said hub, and said anchor being provided with upwardly extending arms, the base plate thereof being a 120 replica of the base plate of the hub; an anvil located in the upper part of said button, and the top plate wedgedly holding the several parts in their fixed positions.

8. A button comprising a top plate, a 125 body, and a hollow hub with an imperforate base at the lower extremity thereof, said base provided with an annular groove spaced a distance from the outer periphery thereof, an anchor located within said hub and pro- 130

vided with upwardly and outwardly extending spring arms, the base plate thereof being a replica of the base plate of the hub; an anvil located in the upper part of said button, 5 and the top plate wedgedly holding the several parts in their fixed positions.

9. A button comprising a body portion with a hollow hub and an imperforate base plate provided with an annular groove and 10 a downwardly extending central portion, an anchor located in said hub, said anchor provided with a plurality of spring arms, said arms being wider at their base than at their

point, and said anchor likewise provided with an annular groove and a downwardly 15 extending central portion; an anvil located in the body portion of said button, and a top plate wedgedly fastened to the upper portion of the body of the button.

Signed at Waterbury, in the county of 20 New Haven and State of Connecticut, this 7th day of April, A. D. 1919.

FRANKLIN R. WHITE.

Witness:

EDNA M. MORTON.
